CLAIM

The ornamental design for a pole connection for a window
cleaning tool, as shown and described.

DESCRIPTION

FIG. 1 is a top, rear, right side perspective view of a pole
connection for a window cleaning tool showing our new
design;

FIG. 2 is a rear elevation view thereof;

FIG. 3 is a front elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a top, front, right side perspective view thereof.
The broken lines in the drawings depict bounds and
environment of the pole connection for a window cleaning tool
that form no part of the claimed design.
